MEANS FOR AND THE METHOD OF
REFRIGERATION

James G. Scott, Washington, D. C.

Application March 4, 1940, Serial No. 322,256

18 Claims. (Cl. 62—89)

This invention relates to improvements in refrigerating apparatus, and particularly to means for and the method of establishing upper and lower compartments within a refrigerator chamber and controlling the variation of temperature between said upper and lower compartments and at the same time maintaining a control over the humidity in the lower compartment.

The primary object is to provide means intended and adapted to be inserted and employed in connection with a refrigerator of ordinary and usual construction including an inclined heat exchange wall mounted across within a refrigerating chamber to divide said chamber into upper and lower compartments, with the inclined wall serving to induce circulation of air in the lower compartment and to conduct flow of water of condensation accumulated thereon to one side where the water may be collected and be prevented from dropping or otherwise finding its way into or upon food in the lower compartment.

Another purpose is to provide a method of controlling variations of temperature between the upper and lower compartments, namely in that the inclined heat exchange wall dividing the chamber into the two compartments is given a greater or steeper inclination to increase temperature differentials and is flattened out or given less inclination to decrease the temperature differentials in the upper and lower compartments.

Still another purpose of this invention is to provide refrigerating apparatus in which the inclined wall is the coldest wall of the lower compartment whereby moisture or humidity in the lower compartment will condense upon this inclined wall and will be induced to flow to one side where the water of condensation is collected and conducted to a desired discharge point.

Yet another purpose of my present invention is to provide an inclined heat exchange wall incorporating a glass plate so that light may penetrate from the upper to the lower compartment, together with means in the form of a supporting shelf carried by and yet out of direct thermal conducting contact with the inclined plate so that foods and other articles can be stored in the upper compartment to rest and be supported on this supporting shelf and consequently out of heat conducting contact with the inclined heat exchange plate, the supporting shelf at the same time serving as a substantially level shelf support in contrast to the inclined heat exchange wall.

Another purpose is to provide means readily inserted within an ordinary refrigerator for supporting the inclined heat exchange wall with the

inclination running across the shorter dimension of the heat exchange wall whereby the heat transfer in the lower compartment will be in such manner as to establish and maintain a circulation of air in planes substantially parallel with the usual door opening for maintenance of better and more uniform refrigeration.

Yet a further object is to provide refrigerating apparatus including a refrigerator chamber having refrigerating means in the upper part thereof with the inclined heat exchange wall disposed below and separated from said refrigerating means and with supplemental cooling means in the lower compartment having condenser means therefor in the upper compartment and spaced from the refrigerating means, with the disposition and spacing of the heat exchange wall and the condenser means so correlated that the inclined heat exchange wall is in fact the coldest wall in the lower compartment, whereby condensation of moisture within the lower compartment will occur primarily only on the lower side of the inclined heat exchange wall.

With the above and other objects in view, some of which will be apparent to those skilled in the art, and others of which are inherent in the construction and use of the apparatus, my present invention includes certain novel features of construction and combinations and arrangements of parts which will be hereinafter set forth in connection with the drawings and then pointed out in the claims.

In the drawings:

Fig. 1 is a view in perspective looking into the open front of a domestic refrigerator showing one adaptation of my invention.

Fig. 2 is an enlarged fragmentary sectional view taken substantially from front to back through the upper part of a refrigerator as in Fig. 1.

Fig. 3 is an enlarged perspective view to better show the construction of the heat exchange division wall.

Fig. 4 is a fragmentary sectional view showing a modification of the heat exchange wall structure.

Fig. 5 is a perspective view similar to Figure 1 illustrating another embodiment of the present invention.

Fig. 6 is an enlarged perspective view to better disclose mounting means for the heat exchange wall.

Fig. 7 is an enlarged fragmentary sectional view taken substantially from front to back

through the upper part of the structure as disclosed in Fig. 5.

In the adaptation illustrated in Figure 1, the refrigerator 1 has the usual storage chamber 2 therein with an evaporator 3 in the upper part of this chamber 2.

The refrigerating unit can be of any desired type and construction, and the usual cold control or adjusting means is provided, as at 4. This chamber 2 is made up of the usual side and top and bottom walls with an opening 5 through the front thereof, and a door 6 is provided to close this opening, any suitable and desired packing and door latch means being employed. The storage chamber 2 is of usual construction and has shelves 7 fitted therein in ordinary manner to be carried by supporting stops 8 or other suitable parts, and in other respects the refrigerator apparatus as illustrated is of usual and ordinary refrigerator construction such as is found in many mechanical or automatic refrigerators as now being manufactured and as already in use.

In the carrying out of my invention the chamber 2 is divided into an upper compartment 9 and a lower compartment 10, by the use of a heat exchange division wall as generally indicated at 11. This heat exchange wall is here shown as being disposed across and between the walls forming the chamber 2, to which chamber access is had through the door opening 5, and when the door 6 is closed this door will serve also as a wall to close and complete the chamber 2. The heat exchange wall 11 fits and extends substantially entirely between the walls on both dimensions so that in effect and reality the compartment 9 is entirely closed off from the compartment 10, and this heat exchange wall 11 is so disposed that it is out of direct conducting contact with the evaporator 3, or other refrigerating means. As ordinarily constructed, the refrigerating means is of such character and capacity that the evaporator 3, or other part within the upper compartment 9 will be capable of normally maintaining within itself a temperature below the freezing point of water, and thus when the ordinary refrigerator is in operation moisture from the air within the chamber 2 will condense and be frozen upon this evaporator 3 or other cold portion of the refrigerator means. Where the refrigerating means frosts, this means that moisture is taken from the air, and as the moisture content of the air is decreased the dehydration or drying out of food-stuffs and the like in the chamber 2 will be increased. However, with the heat exchange wall 11 interposed to divide the chamber into the upper compartment 9 around the evaporator 3 and the lower compartment 10 closed so that the air thereof cannot circulate around the evaporator 3, it is impossible for any air in the compartment 10 to circulate in or around the refrigerating means, and if the operation be maintained so that the heat exchange wall 11 is at a temperature above the freezing point of water, there will be no freezing or frosting upon any wall or other part of the structure within the compartment 10. Consequently, if there be no freezing or frosting there will be no consequent decrease in humidity within the compartment 10.

With the parts constructed and used in the manner above set forth, the low temperature upper compartment 9 will be a cold dry compartment for storage of foods and the like requiring low temperatures, and the higher temperature lower compartment 10 will be a general food storage compartment, as for ordinary foods and

leafy vegetables and the like, with assurance of maintenance of a humid cold, since there is no possibility of frosting and of consequent extraction of moisture from the compartment.

This heat exchange wall 11 has a supporting frame structure 12, of metal or of other suitable material, and provided with inclined supporting ledges 13 at opposite sides. A heat exchange plate 14 is fitted and is supported on these supporting ledges 13 so that this plate is appreciably inclined, and as the heat exchange plate 14 constitutes the major portion and area of the heat exchange wall structure 11, this inclined plate 14 is disposed and serves substantially as an inclined ceiling for the lower compartment 10. Through tests and experiments I have found that by inclining the heat exchange plate 14 from front to back I preserve a maximum storage space within the compartment 10 and at the same time provide for circulation of air within this compartment due to the fact that the inclination of the ceiling, as consisting primarily of the plate 14, will induce and will cause a natural flow and circulation of air within the compartment 10 with the up and down paths of flow of air substantially parallel with the door opening so that as the air is circulated the natural course is to carry out this circulation within the confines of the compartment 10, even with the door 6 opened.

As has been stated, the heat exchange plate 14 of the heat exchange wall structure 11 is maintained at a temperature above the freezing point of water, and this is readily accomplished since the heat exchange wall structure is below and is spaced from the evaporator 3 or other refrigerating means and the heat exchange effected from the plate 14 to the compartment 9 is by convection. With the heat exchange wall structure, and the plate 14, maintained at a temperature above the freezing point of water and this plate maintained as the coldest wall within the compartment 10, any excess moisture within the compartment 10 will collect as water of condensation on the lower side of the plate 14. The inclination of this plate 14 will influence or induce gravity flow of this water of condensation toward the low side of the inclined plate, and there will be no possibility of moisture of condensation collecting in sufficiently large drops to separate from the plate 14 and fall into or upon foods and the like upon the shelves 7 or within the part 10. It is desirable that any water of condensation conducted to the low side by the inclination of the plate 14 be conducted off to a single point, and with this in mind I provide a drip or drain trough 15 at the lower side or edge of the plate 14 where it will catch water flowing to the low side and will conduct this to a common discharge point. It has been found that an ordinary water glass or other suitable receptacle can be placed, as generally indicated at 16 in Figure 1, upon one of the shelves 7 and at a back corner where it will be out of the way and will catch the water discharged from the trough or drain 15.

The heat exchange wall structure 11 can be made of substantially exact sizes and dimensions to close sufficiently tightly within the chamber 2 and between the walls thereof to close off the compartments 9 and 10, or if conditions require packing may be provided as at 17. Further, while the heat exchange wall structure is illustrated as provided with a frame 12 variations can be resorted to so that the inclined plate portion 14 will be supported in proper position and inclination, in other manners, and will extend

substantially entirely across between the walls.

With the parts constructed and assembled in the manner set forth, the inclined heat exchange wall structure will serve to induce and maintain a natural circulation of air within the compartment 10, and in carrying out the method of my invention the differential of temperature variation between the upper compartment 9 and the lower compartment 10 can be controlled by increasing or decreasing the angle of inclination of the plate or wall portion. Thus, as the plate portion 14 is given less inclination, substantially to the flattened angle indicated at *a* in Fig. 2, the temperature differential between the upper and lower compartments will be decreased, and as the angle of inclination is increased or made sharper, as indicated at *b* in Fig. 2, the temperature differential between the upper and lower compartments will be increased, since the circulation of air against the inclined plate 14 within the compartment 10 is accelerated. If it be desired to provide for more possible variations in inclination, adjusting means similar to that shown in Fig. 24 of the drawings of my co-pending application Serial No. 228,433, or of any other desired or suitable form, can be employed.

Also, it will be appreciated that temperature differentials, between the upper compartment 9 and the lower compartment 10, will be varied according to the material employed in construction of the inclined plate 14. I have found that sheet glass presents particular advantages for use as the heat exchange wall or plate 14, since it is customary to place refrigerator lighting lamps in the upper part of the refrigerator chamber, and where the plate 14 is of glass this will permit illumination of substantially all parts of the refrigerator chamber, both in the upper compartment 9 and the lower compartment 10.

Through extensive experiments and tests carried out over a considerable period of time, I have found that the temperature differential between the upper compartment 9 and the lower compartment 10 can be varied by the use of different materials for construction of the heat exchange wall or plate 14, as for instance, metals such as copper, aluminum, and other metals and materials. Further, the temperature differential can be regulated and varied by changes in the surface formation or configuration of the plate 14, to thus change the area of the surface presented for convection contact.

As the heat exchange wall or plate structure, generally indicated at 11, is spaced from the evaporator 3, or other refrigerating means in the upper compartment 9, there is no direct conduction heat exchange, and heat absorption from the wall structure 11 to the evaporator or refrigerator means 3 is by convection. Thus, while the refrigerating means is capable of maintaining a temperature below the freezing point of water, and the evaporator 3 will ordinarily be operated in such manner that moisture in the air would accumulate as frost on the evaporator surfaces, with the heat absorption from the plate 11 accomplished through convection, this heat exchange wall structure 11 is maintained at a temperature above the freezing point of water, and consequently there will be no frosting upon the heat exchange wall or plate within the lower compartment 10. Further, since the heat exchange wall structure 11, and the inclined plate portion 14 will be maintained as the coldest wall within this lower compartment 10, there will be no condensation of moisture upon the side or bot-

tom walls within the compartment 10, and any condensation will be only upon the underside of the heat exchange wall 11 and inclined plate 14. As this wall 11 is maintained at a temperature above the freezing point of water, there will be no frosting on the lower side of this wall or plate structure and the only effect will be that excess moisture in the air in the lower compartment 10 will condense and accumulate on the underside of the inclined plate 14 and will flow by gravity along the inclination thereof to the low side where it will be caught by the drip trough 15.

Through long and exhaustive experiments conducted over a considerable period of time I have found that a heat exchange wall or plate disposed in a substantially horizontal plane will accumulate water of condensation on the lower side, and that as this water of condensation accumulates it will form in drops so that as the drops become sufficiently large to break the surface tension they will fall or drip at random into and through the lower compartment 10, thus discharging water into or over foodstuffs within this compartment 10 or upon the shelves 1. My experiments and tests conclusively show and prove that with the parts constructed and operated in the manner set forth above, the air within the lower compartment 10 will be maintained in a moist or humid condition, thus giving a moist atmosphere and ideal conditions for storage and preservation of foodstuffs in the lower compartment 10, and creating a cold moist atmosphere particularly suitable for preserving fruits and vegetables, and especially leafy materials, in fresh and moist condition without danger or possibility of deterioration through dehydration or other accumulation of excessive moisture. My extensive tests prove that this structure when in use removes excessive moisture from the air within compartment 10, and does not remove moisture excessively. In these experiments I have preserved and maintained spinach and celery and other leafy vegetables and other foods containing a considerable proportion of water in substantially garden-fresh and moist condition, for periods of several days, and without the usual tendency to fading in the color or the usual spoilage due to drying out exposed surfaces or softening and deterioration where water or excessive moisture has accumulated.

As has been stated, the heat exchange wall structure 11, and especially the plate portion 14, absorb heat by convection from the lower compartment 10, and then by convection the heat within this structure is absorbed into the compartment 9, the evaporator or other refrigerating structure 3 there serving to absorb the heat within this upper compartment 9. Since the wall structure 11 and the plate 14 are exposed to absorb heat from the lower compartment 10, if foodstuffs or other materials be placed within the upper compartment 9 to rest directly upon or to be in thermal conducting contact with these portions, such foodstuffs or materials will absorb or take up heat from the lower compartment 10 and will not and cannot be maintained at the temperature of the compartment 9.

Therefore, I have found it advantageous to prevent placement or contact of any foodstuffs or any other materials within the compartment 9 in such relation that they will conductively contact the heat exchange wall structure 11. To this end, I provide a support or shelf or rack structure 18 to be spaced above and out of conducting contact with the heat exchange wall

structure 11. As illustrated, the support or rack 18 is carried by insulating legs 19 so that there is no thermal conducting contact with the heat exchange wall structure 11.

With the modified construction shown in Fig. 4, the supporting frame structure 20 has two inclined plate supporting portions, and the plate 21 is maintained on one of these supporting structures to separate or divide off the upper and lower compartments. The lower plate 22, preferably inclined with respect to the plate 21, is made to be of a shorter dimension than the plate 21, and thus openings are provided at each side, as the plate 22 is inclined or canted, and in consequence a natural thermal circulation of air within the lower compartment 18 will be accomplished and will be maintained.

With the adaptation illustrated in Fig. 6, the heat exchange wall structure is applied and is supported by means readily adapted to and mounted in domestic refrigerators of some types now being manufactured. As here shown, a substantially U-shaped supporting frame structure is made up with the side or arm portions 31 and 32 thereof adapted to be received substantially flatwise against the opposite side walls of a refrigerator, and openings 33 are provided to receive screws or bolts or other fastenings by which the supporting frame will be mounted in place. In some types of refrigerators the shelves or other supporting means are supported by channeled portions held in place by screws or similar fastenings and the openings 33 of the side bars 31 and 32 can be spaced to register with openings in an ordinary refrigerator left by removal of the usual or ordinary shelf supporting means, as above described; or, openings can be provided in any desired or necessary spacing and the supporting frame structure can be mounted within the refrigerator chamber and between the side walls thereof in any desired and approved manner. These side members or portions 31 and 32 have inclined supporting flanges 34, which flanges are inclined or canted downwardly toward the cross bar portion 35. The cross bar portion 35 of the substantially U-shaped frame structure has the drip or drain trough 36 carried thereby and inclined downwardly toward one side. In the use of this adaptation, the supporting frame structure is mounted in a refrigerator cabinet, in place of the usual shelf supporting means, or at any other desired location; and, when the heat exchange wall 37 of sheet glass or other suitable sheet material, is fitted to rest upon the inclined supporting flanges 34, this heat exchange plate 37 will be correspondingly inclined and the lower edge will be disposed over the drip or drain trough 36. In this manner the heat exchange plate 37 is inclined in such manner that moisture of condensation accumulating on the underside will flow by gravity toward the lower side or edge and any drippage will be caught in the trough 36 and will be conducted thereby to a desired discharge point or location. The side bars or portions 31 and 32, and also the cross bar portion 35, can be provided with supporting flanges 38 to receive and support a shelf similar to the shelf 18 so that foodstuffs and the like will not come into direct conducting contact with the heat exchange plate 37. Further, it may sometimes be found desirable to provide a double wall, and under such circumstances a second plate, similar to the plate 37, can be inserted to rest and be supported upon the flange portions 38. In this assembly the two plates will be separated one from the other so

that there will not be direct thermal conduction, and in fact a dead air space will be provided between the two plates. As a further adaptation the supporting frame structure can be employed in such manner that the upper flanges 38 support a plate similar to the plate 22 illustrated in Fig. 4, and a second plate, similar to plate 22 of Fig. 4, can be placed upon the supporting flanges 34 with two opposite edges separated from the refrigerator walls to thus provide circulation, somewhat as set forth in connection with the disclosure of Fig. 4.

As the parts are illustrated in Figs. 5 and 7, the supporting frame structure disclosed in Fig. 15 6 is shown, but it will be appreciated that this is only for convenience of exposition of other parts and that other manners of constructing the heat exchange wall or plate member can be resorted to.

In this disclosure the refrigerator 23 has an evaporator 24, or other suitable refrigerating means ordinarily capable of producing a temperature below the freezing point of water, disposed in the usual location in the upper part of the refrigerator chamber 25, or placed in any other desired location to permit mounting of the heat exchange wall 28 between the walls of the refrigerator chamber to divide said chamber into an upper compartment 29 around the refrigerating means 24 and a lower compartment 30 separated therefrom. The refrigerator has supplemental cooling means for this lower compartment 30 and this supplemental cooling or second refrigerating means is here shown as having coils 26 or other means within the refrigerator walls or otherwise disposed so that they will influence the temperature in the compartment 30. A condenser structure 27 is connected with the coils 26 and this condenser is disposed within the compartment 29 adjacent to the evaporator or refrigerating means 24, but sufficiently spaced therefrom to provide convection cooling. In the present instance I have shown the condenser or cooling means 27, for the cooling coil or second refrigerating means 26, as located below the evaporator or refrigerating means 24, but this is intended to be only illustrative, and the condenser structure 27 can be mounted or disposed above or laterally with respect to the evaporator 24. With this modified adaptation, as the evaporator 24 extracts heat from the upper compartment 29, the air within this compartment is chilled and by convection the condenser structure 27 will be correspondingly chilled so that the coils 26 connected in closed refrigerating systems with the condenser 27 will be reduced in temperature to absorb heat from and lower the temperature of the air in the lower compartment 30. To attain desired utility of this adaptation, the heat exchange wall 28 is maintained as the coldest wall of the compartment 30, and must be held at a temperature such that water will not freeze thereon. To this end, I so disposed the heat exchange wall 28 and the condenser or cooling portion 27, relatively, and with respect to the evaporator or refrigerating means 24, that the cooling coil 26 and the side and bottom walls of the compartment 30 will be maintained at temperature higher than the temperature of the heat exchange wall 28. Thus, since this heat exchange wall 28 is the coldest wall in the compartment 30, any excess moisture in the air in this compartment 30 will be collected as water of condensation on the lower side of the inclined portion of the heat exchange wall 28 and the accu-

mulated water will flow by gravity toward the low side and will be prevented from dropping or dripping promiscuously into or over foodstuffs and the like within the compartment 30. Thus, excess moisture in the air in the compartments 30 will be removed without danger of dilution or contamination of or damage to materials stored therein and since the side and bottom walls of compartment 30 are maintained at relatively higher temperature than the heat exchange wall 28, tendency to condensation and sweating upon these walls is avoided, and moisture is not removed from the air in the compartment 30 excessively.

With the embodiment of the single heat exchange wall or plate 14, I have found that I can conveniently and readily attain and maintain a differential of approximately fifteen degrees, in the temperature between the upper compartment 9 and the lower compartment 10, so that with the control 4 set to maintain a temperature of around thirty degrees Fahrenheit in the upper compartment, which has been found desirable for keeping meats and bottled goods, and many other foods and products, I can attain and maintain a temperature of around forty-five degrees in the lower compartment 10. As has been set forth, variation in the inclination or canting of the plate 14 has been found to give variations in the temperature as maintained in the lower compartment 10.

With the structure as disclosed in Fig. 4, I have found that the lower plate 22 accomplishes a greater differential in temperatures between the upper and the lower compartments, and in experiments as conducted this differential has been around thirty degrees, so that when the upper compartment is maintained at around ten degrees Fahrenheit, suitable for storage of frosted foods and the like, this relatively larger differential in temperature will permit maintenance of the temperature in the lower compartment at around forty degrees, this being within the range now commonly understood and accepted as being the best for preservation of foodstuffs in a general foodstuff storage refrigerator. By increasing or decreasing the size of the lower plate 22, and perhaps the inclination thereof, this temperature differential between the upper and lower compartments can be further varied.

Referring again to the adaptation shown in Figs. 5 and 7, the coils or supplemental cooling means 26, in the lower compartment 30, may not serve strictly as refrigerating means, in the commonly accepted sense of being the sole source of heat exchange, and this supplemental cooling means will function to guard against or equalize for heat infiltration through the refrigerator walls.

With the mounting or supporting frame structure as shown in Fig. 6, it is possible to place a single plate 37 to be supported by the inclined supporting flanges 34, or to rest a single plate upon the upper supporting flanges 38, and thus the inclination of the single plate can be varied to accomplish desired temperature differentials. Further, with this construction a plate can be mounted on the upper supporting flanges 38 and a second plate, of the same or of less width, can be mounted on the supporting flanges 34, and additional relative temperature variations can thus be accomplished.

While I have herein shown and described only certain specific embodiments of my invention and have set forth only certain specific modifications

in structure and adaptation, it will be appreciated that many changes can be made in the form, construction and arrangement of the parts and in the manner of use and association with refrigerator cabinet and other structures, without departing from the spirit and scope of my invention.

I claim:

1. A refrigerator comprising a chamber, refrigerating means in the upper part of the chamber, and a heat exchange wall mounted within the chamber beneath and out of contact with the refrigerating means thus dividing the chamber into non-communicating upper and lower compartments the lower surface of said wall being of such character and being inclined sufficiently to cause flow of water of condensation accumulated on said heat exchange wall within the lower compartment to one side.
2. A refrigerator comprising a chamber, refrigerating means in the upper part of the chamber, a heat exchange wall mounted within the chamber beneath and out of contact with the refrigerating means thus dividing the chamber into upper and lower compartments and cutting off air circulation therebetween the lower surface of said wall being of such character and being inclined sufficiently to cause flow of water of condensation accumulated on said heat exchange wall within the lower compartment to one side, and supporting structure above said inclined heat exchange wall out of direct conducting contact therewith.
3. A refrigerator comprising a chamber, refrigerating means in the upper part of the chamber, and a glass plate mounted across and within the chamber beneath and out of contact with the refrigerating means thus dividing the chamber into non-communicating upper and lower storage compartments, said plate being disposed and held in inclination from a horizontal plane sufficient to cause flow of water of condensation accumulated on the lower side thereof.
4. A refrigerator comprising a chamber, refrigerating means in the upper part of the chamber, a glass plate mounted across and within the chamber in inclination from a horizontal plane beneath and out of contact with the refrigerating means thus dividing the chamber into non-communicating upper and lower compartments, said plate being inclined sufficiently to influence gravity flow of water of condensation accumulated thereon within the lower compartment to one side, and means to conduct the water of condensation to a common point.
5. A refrigerator comprising a chamber, refrigerating means in the upper part of the chamber, an inclined glass plate mounted within the chamber beneath and out of contact with the refrigerating means thus dividing the chamber into non-communicating upper and lower compartments, said plate being inclined sufficiently to cause flow of water of condensation accumulated on the lower side thereof and supporting structure above said inclined glass plate and out of direct conducting contact therewith.
6. A refrigerator comprising a chamber, refrigerating means in the upper part of the chamber, a glass plate mounted within the chamber beneath and out of contact with the refrigerating means thus dividing the chamber into upper and lower compartments substantially cutting off air circulation therebetween and inclined sufficiently to induce gravity flow of water of condensation accumulated on said glass plate within the lower

compartment to one side, and supporting structure above and out of direct conducting contact with said glass plate.

7. With a refrigerator having a walled chamber and having refrigerating means in the upper part of the chamber, a supporting frame carried by certain walls of said chamber beneath the refrigerating means and provided with guideways inclined from a horizontal plane, and a heat exchange wall mounted in said guideways beneath and out of contact with the refrigerating means thus dividing the chamber into upper and lower compartments.

8. With a refrigerator having a walled chamber and having refrigerating means in the upper part of the chamber, a supporting frame carried by certain walls of said chamber beneath the refrigerating means and provided with guideways inclined from a horizontal plane, a heat exchange wall mounted in said guideways beneath and out of contact with the refrigerating means thus dividing the chamber into upper and lower compartments and inclined sufficiently to induce gravity flow of water of condensation accumulated on said heat exchange wall within the lower compartment toward one side of said wall, and drip catching means at the low side of said heat exchange wall.

9. With a refrigerator having a walled chamber and refrigerating means in the upper part of the chamber, a substantially U-shaped supporting frame mounted on certain walls of said chamber below the refrigerating means and provided with inclined guideways on the inner sides of the arms of the U-shaped form, and a heat exchange wall mounted within the guideways and consequently inclined from a horizontal plane.

10. With a refrigerator having a walled chamber and refrigerating means in the upper part of the chamber, a substantially U-shaped supporting frame mounted on certain walls of said chamber below the refrigerating means and provided with inclined guideways on the inner sides of the arms of the U-shaped form, a heat exchange wall mounted within the guideways and consequently inclined from a horizontal plane, said heat exchange wall being held inclined in a direction to induce gravity flow of water of condensation accumulated on the lower side thereof toward the cross bar of the U-shaped frame, and water conducting means to receive the water of condensation thus directed by and from the heat exchange wall.

11. A refrigerator comprising a cabinet, a plurality of walls defining a chamber in said cabinet, mechanical refrigerating means in the upper part of said chamber operable to produce a temperature below the freezing point of water, a heat exchange wall mounted within the chamber beneath the refrigerating means dividing said chamber into upper and lower compartments, and cooling means in heat exchange relation with respect to the lower compartment, and condenser means for said cooling means within the upper compartment, spaced from and cooled by said refrigerating means by convection, said heat exchange wall being cooled by convective circulation of air, being normally the coldest wall presented within the lower compartment and being normally maintained within a temperature range above frosting within which range moisture from the storage compartment will condense on said heat exchange wall and will not freeze.

12. A refrigerator comprising a chamber, refrigerating means in the upper part of the chamber

ber operable to produce a temperature below the freezing point of water, a heat exchange wall within said chamber beneath said refrigerating means dividing the chamber into upper and lower compartments, a second refrigerating means within the lower compartment below the heat exchange wall, cooling means connected with said second refrigerating means located within the upper compartment and spaced from conducting contact with respect to the refrigerating means, said heat exchange wall being normally the coldest wall of the lower compartment and being normally maintained within a temperature range above frosting, said heat exchange wall being inclined from a horizontal plane to induce gravity flow of water of condensation accumulated on the lower side of said wall toward one side, and means to conduct the water of condensation to a common collection point.

13. A refrigerator comprising a walled chamber, refrigerating means in the upper part of the chamber operable to produce a temperature below the freezing point of water, a heat exchange wall mounted within the chamber beneath the refrigerating means dividing said chamber into upper and lower compartments, cooling means within the walls of the lower compartment and by which the temperature of said walls is reduced, and condenser means for said cooling means within the upper compartment adjacent to and spaced from the refrigerating means, said heat exchange wall being cooled by convective circulation of air and being normally the coldest wall of the lower compartment and being normally maintained within a temperature range above frosting.

14. A refrigerator comprising a walled chamber, refrigerating means in the upper part of the chamber operable to produce a temperature below the freezing point of water, a heat exchange wall mounted within the chamber beneath the refrigerating means dividing said chamber into upper and lower compartments, cooling means within the walls of the lower compartment and by which the temperature of said walls is reduced, and condenser means for said cooling means within the upper compartment adjacent to and spaced from the refrigerating means, said heat exchange wall being normally the coldest wall of the lower compartment and being normally maintained within a temperature range above frosting, and said heat exchange wall being inclined sufficiently to induce gravity flow of water of condensation accumulating upon said wall within the lower compartment to one side.

15. A refrigerator comprising a chamber, refrigerating means in the upper part of the chamber, a glass plate mounted across and within the chamber in inclination from a horizontal plane beneath and out of contact with the refrigerating means thus dividing the chamber into upper and lower compartments and cutting off air circulation between said compartments, and an air circulating plate also in inclined relation from a horizontal plane beneath and out of contact with and spaced adjacent to said glass plate and with its edges at the top and the bottom of the inclination spaced from adjacent walls within the lower compartment.

16. A refrigerator comprising a chamber, refrigerating means in the upper part of the chamber, a glass plate mounted across and within the chamber in inclination from a horizontal plane beneath and out of contact with the refrigerating means thus dividing the chamber into upper

and lower compartments and cutting off air circulation between said compartments, an air circulating plate also in inclined relation from a horizontal plane beneath and out of contact with and spaced adjacent to said glass plate and with its edges at the top and the bottom of the inclination spaced from adjacent walls within the lower compartment, and supporting structure above said inclined heat exchange wall out of direct conducting contact therewith.

17. With a refrigerator having a walled chamber and refrigerating means in the upper part of the chamber, a substantially U-shaped supporting frame mounted on the walls of said chamber below the refrigerating means and provided with upper and lower pairs of inclined guideways on the inner sides of the arms of the U-shaped form, a heat exchange wall mounted in the upper guideways and, consequently inclined from a horizon-

tal plane, and an air circulation wall mounted in the lower set of guideways and spaced below the heat exchange wall and having its opposite edges intermediate the supporting guideways spaced from the adjacent walls of the chamber.

18. A refrigerator comprising a storage chamber, refrigerating means in the upper part of the chamber, a heat exchange wall mounted across within and beneath and out of contact with the refrigerating means dividing the chamber into non-communicating upper and lower storage compartments, said heat exchange wall functioning by convective circulation of air and being disposed obliquely from a horizontal plane and having the inclination thereof made steeper and flatter as may be desired to reduce and to increase the temperature differential between the upper and lower compartments.

JAMES G. SCOTT.
